7 Claims. (Cl. 103—153)

This is a continuation of application Ser. No. 388,205
filed Aug. 7, 1964, now abandoned.

This invention is concerned with improvements in
or relating to piston operated pumps adapted to pump
liquid carbon dioxide.

Piston operated pumps adapted to pump liquid carbon
dioxide have been known for a number of years. These
pumps are not entirely satisfactory in that liquid carbon
dioxide tends to leak from the pumping chamber be-
tween the piston and cylinder wall where, due to the
sudden reduction in pressure, it changes to gas and solid.
The presence of the solid carbon dioxide between the
piston and cylinder wall causes wear and unsatisfactory
pumping action. The term cylinder wall used through-
out this specification includes any surfaces encircling the
piston, such as for example sealing surfaces.

An object of the present invention is to provide an
improved piston operated pump in which the disadvan-
tage hereinbefore described is either reduced or elimi-
nated.

Accordingly the present invention is a piston operated
pump adapted to pump liquid carbon dioxide wherein
a device is provided which is capable of applying a gas
under pressure to any liquid carbon dioxide which leaks
from the pumping chamber between the piston and cylin-
der wall, said pressure being sufficient to prevent liquid
carbon dioxide from solidifying between the piston and
cylinder wall.

The device is preferably an annular recess in the wall
of the cylinder below the piston head which forms a
cavity in combination with the piston and a passageway
in the wall through which fluid under pressure can be
supplied to the cavity. A sealing gland or glands are pref-
erably provided in this cavity which reduce the tendency
for liquid carbon dioxide to leak past the piston. The
passageway which connects this cavity and the outside
of the cylinder can be formed by a hole bored through
the cylinder wall. Gas can be supplied through this pas-
sageway to the cavity to give a pressure sufficient to pre-
vent any liquid carbon dioxide which leaks between the
piston and the cylinder wall from solidifying.

Any pressure greater than the pressure at the triple
point pressure of any carbon dioxide which has leaked
between the piston and cylinder wall is suitable. When
the pump is operated at ambient temperatures a suitable
pressure is between 200 and 800 pounds per square inch.
This is the pressure range under which liquid carbon
dioxide is normally stored. Thus in a preferred embodiment
the device is supplied with carbon dioxide by con-
necting it to a container of liquid carbon dioxide, for
example the liquid carbon dioxide which it is desired
to pump.

The preferred gas is carbon dioxide. When the device
is an annular recess in the cylinder wall as hereinbefore
described the carbon dioxide can be supplied to the cavity
as a liquid where it forms the gas under pressure under
the influence of the heat generated by the pump as soon
as it is operated.

An embodiment of the present invention is illustrated
in the accompanying drawing which shows a longitudi-

2

nal section of a piston operated pump. The pump con-
sists of a body 1 formed internally into a cylinder with
a cylinder wall 3 and a piston 2 attached to a crank 4
within the cylinder. One end of the cylinder is formed
into a pumping chamber 5 which is provided with an
inlet valve 6 and exit valve 7 to allow liquid carbon
dioxide to enter and leave the pumping chamber. The
cylinder wall is provided with an annular recess 8 which
forms a cavity 9 in combination with the piston. A gland
10 is provided in this cavity at the end nearest to the
pumping chamber. This gland forms a seal which reduces
the amount of liquid carbon dioxide entering the cavity
from the pumping chamber. A gland 11 is provided at the
other end of the cavity to prevent or retard the escape of
carbon dioxide gas from the cavity. A passageway 12 is
formed between the cavity and the outside of the cylin-
der by a hole bored through the cylinder wall. This pas-
sageway allows gas under pressure to pass into the cavity.

In operation when piston 2 is lowered liquid carbon
dioxide is drawn into the pumping chamber 5 through
an inlet valve 6 from a container in which it is stored
under a gas pressure of approximately 300 pounds per
square inch. It is then forced out of the pumping chamber
through outlet valve 7 when piston 2 is raised. During
this reciprocating movement of the piston cavity 9 is
pressurised to a pressure of 300 pounds per square inch
by carbon dioxide gas from the container. Any liquid
carbon dioxide which leaks from the pumping chamber
5 between the piston and cylinder wall past gland 10 is
30 prevented from expanding to form solid carbon dioxide
by the pressure of carbon dioxide in cavity 9.

I claim:

1. A piston pump apparatus adapted to pump liquid car-
bon dioxide, comprising a cylinder member having a
35 pumping chamber therein, a piston member reciprocally
slidable within the cylinder member to pump fluid from
the pumping chamber, the members having sizes such that
liquid carbon dioxide leaks from the chamber between the
members, at least one of said members having a cavity
40 therein opening laterally against the other member, a
source of gas under a pressure greater than the triple
point pressure of the carbon dioxide being pumped, and
conduit means coupling said source of gas and said cavity
45 for applying the gas under said greater pressure to the
space between the piston member and the cylinder mem-
ber wall, whereby when said gas is supplied to the cavity
and applied to the liquid carbon dioxide which leaks from
50 the pumping chamber between the piston member and the
cylinder member wall, it will prevent liquid carbon
dioxide from solidifying between the piston member and
cylinder member wall.

2. A pump apparatus as claimed in claim 1 in which
the cavity is an annular recess in the cylinder member
wall below the piston member head, and said conduit
55 means includes a passageway in the wall through which
the gas under pressure can be supplied to the cavity.

3. A pump apparatus as claimed in claim 2 in which
the cavity has a sealing gland at the end thereof toward
the piston member head which reduces the tendency of
60 liquid carbon dioxide to leak past the piston member.

4. A pump apparatus as claimed in claim 1 in which
the source of gas under pressure is a source of carbon
dioxide.

5. A process for pumping liquid carbon dioxide which
65 comprises supplying liquid carbon dioxide to the pumping
chamber of a piston pump and operating the pump, and
simultaneously applying a gas to any liquid carbon
dioxide which leaks from the pumping chamber between the
piston and cylinder wall at a pressure greater than the
70 triple point pressure of the carbon dioxide being pumped,
whereby the liquid carbon dioxide is prevented from
solidifying between the piston and cylinder wall.

6. A process as claimed in claim 5 wherein the applied gas is carbon dioxide.
7. A process as claimed in claim 5 wherein the gas is carbon dioxide formed from liquid carbon dioxide under the influence of heat generated by the pump when it is operated.
